FOLDING CHAIR

Filed Dec. 3, 1925

William C Rastetter INVENTOR

BY

A. G. Burns ATTORNEY

UNITED STATES PATENT OFFICE.

WILLIAM C. RASTETTER, OF FORT WAYNE, INDIANA.

FOLDING CHAIR.

Application filed December 3, 1925. Serial No. 72,886.

This invention relates to improvements in folding chairs and the object thereof is to provide a chair the seat, legs and back of which may be folded into substantially a common plane. Another object is to provide a folding chair structure of extreme simplicity with folding parts so connected in relation with each other that the rigidity of the structure will be increased by the weight of the occupant.

These objects are accomplished by the construction illustrated in the accompanying drawings, in which:—

Fig. 1 is a side elevation of a folding chair embodying the invention; and

Fig. 2 is a front elevation projected from Fig. 1.

The characters appearing in the description refer to parts shown in the drawings and designated thereon by corresponding characters.

The invention comprises a seat frame 1 having a cross rod 2 extending therethrough at a point spaced from the front end of the frame, upon which rod a pair of fore-legs 3 are pivoted at their upper ends. A pair of rear legs 4 are pivoted at their upper ends respectively to the corresponding sides of the seat frame 1 at a point spaced from the rear end thereof, as indicated by 5, the said rear legs 4 being spaced farther apart than the fore-legs 3 so that the latter may be received between the former legs when folded. The rear legs are each connected to the corresponding fore-leg by a strut 6 being pivoted to the corresponding rear leg at a point suitably spaced from the lower end thereof as indicated by 7, upon the inner side thereof, and the opposite end of the strut being pivoted to the corresponding foreleg, as indicated by 8, upon the outer side thereof. The length of each strut is equal to the distance between its pivotal connection 7 with the rear leg and the pivotal connection 5 between said rear leg and seat frame. The pivotal connection 8 of said strut on the fore-leg is spaced from the connection 2 of the upper end of the leg and seat frame, a distance equal to that between the pivotal connections 2 and 5 of the fore-leg and rear leg in the seat frame. By thus disposing the pivotal connections between the fore and rear legs and the seat and between the strut and said legs, the seat, fore-legs and struts

will fold into substantially a common plane, 55 with the struts positioned between the corresponding legs.

The forward legs and the rear legs are disposed when the chair is unfolded to its position for use, so that the fore-legs slant 60 downwardly toward the front, and the rear legs slant downwardly in the opposite direction with somewhat greater declivity than that of the fore-legs. Also, the legs slant outwardly toward their lower ends. Thus, 65 when occupied the chair is braced so as to resist forward and rearward, as well as lateral swaying motion of the occupant.

A back frame 9 having side members 10 has pivoted connections at the lower ends of its side members 10 respectively with the corresponding rear legs 4 at corresponding points thereon between the seat frame and struts, as indicated by 11, and has sliding connection with the rear end 12 of the seat 70 frame, there being a laterally disposed stud 13 on each side of the seat frame that projects into an elongated slot 14 in the corresponding side member 10 of the back frame and in which said stud has sliding movement. The upper ends of said slots terminate at such points as to limit the unfolding movement of the seat frame on its pivotal connections with the rear legs when the seat reaches horizontal position. 75

When the seat is moved in the opposite direction, or folded, the back frame is swung upon its pivotal connection with the rear legs into the plane of the rear legs through the action of the studs in said slots. 80

A back rest 15 is secured at its top in the upper part of the frame 9 and at its bottom to a cross bar 16 that connects the side members of said frame. 85

In utilizing the invention the seat is 90 turned outwardly while the back frame is swung rearwardly, which has the effect also of imparting a forward swinging movement to the fore-legs limited by the struts. While the legs rest upon the floor and the weight 100 of the occupant is on the seat, forward and backward swaying movement of the chair is obviated by the struts connecting the fore and rear legs, and the studs on the rear end of the seat which have limited upward movement in the side members of the back frame. When the chair is not required for use it is 105 folded by raising the front end of the seat

and swinging it into the back frame which has the effect of also folding the legs and struts into a common plane therewith.

What I claim is:—

- 5 1. In a folding chair, a seat frame; a pair of fore-legs having pivotal connections at their upper ends upon a common axis with said frame in the forward part thereof; a pair of rear legs having pivotal connection 30
10 at their upper ends upon a common axis in said frame at a point therein spaced from the axis of the forelegs; a strut connecting each rear leg with the corresponding fore-leg, said strut being pivoted to the inner 35
15 side of the rear leg near its lower end and to the corresponding fore-leg upon the outer side thereof; a back frame having side members the lower ends of which have connections respectively with said rear legs and 40
20 sliding connection with the rear end of said seat frame, the movement of which sliding connections is limited; and a back rest supported by said back frame.
2. A folding chair comprising a seat 45
25 frame; a pair of fore-legs pivotally connected with the seat frame in the forward part thereof; a pair of rear legs pivotally

connected with the seat frame at a point therein spaced from the connection of the forelegs with said frame; a strut connecting each rear leg with the corresponding fore-leg so disposed as to admit of folding of the fore and rear legs with the seat; and a back member having pivotal connection with said rear legs and a connection with the rear 50 end of said seat frame having limited sliding movement in the back member.

3. A folding chair comprising a seat frame; a pair of folding fore-legs in connection with the seat frame in the forward 40 part thereof; a pair of folding rear legs in connection with the seat frame at a point therein spaced from the connection of the forelegs with said frame; a strut connecting each rear leg with the corresponding foreleg 45 and a back member having pivotal connection with said rear legs and a connection with the rear end of the seat frame admitting of limited sliding movement therebetween. 50

In testimony whereof I affix my signature.

WILLIAM C. RASTETTER.
